United States Patent Office

Des. 204,901
Patented May 24, 1966

204,901

LAMP HOLDER

Leonard Atkin, Springfield, and Charles Roth, Scotch Plains, N.J., assignors to Stonco Electric Products Company, a corporation of New Jersey

Filed May 11, 1965, Ser. No. 85,227

Term of patent 14 years

(Cl. D48—20)

FIG. 1

FIG. 2

FIG. 3

FIG. 4

FIG. 5

FIG. 6

FIGURE 1 is a side elevational view of one side of a lamp holder showing our new design;

FIGURE 2 is a top view thereof;

FIGURE 3 is a bottom view thereof;

FIGURE 4 is a side elevational view of another side thereof;

FIGURE 5 is a front elevational view thereof; and

FIGURE 6 is a rear elevational view thereof.

We claim:

The ornamental design for a lamp holder, substantially as shown.
